FIG. 1

FIG. 2

FIG. 3

FIG. 4

FIG. 5

William J. Newton Inventor,

By his Attorney,

Emery, Bowditch, Janney & Keeney

UNITED STATES PATENT OFFICE.

WILLIAM J. NEWTON, OF LYNBROOK, NEW YORK, ASSIGNOR, BY MESNE ASSIGNMENTS, TO JOHN G. LIVINGSTON, OF WOODMERE, LONG ISLAND, NEW YORK.

SWITCH OR RECEPTACLE BOX.

1,345,503.

Specification of Letters Patent.

Patented July 6, 1920.

Application filed December 5, 1916. Serial No. 135,135.

To all whom it may concern:

Be it known that I, WILLIAM J. NEWTON, a citizen of the United States, and a resident of the village of Lynbrook, county of Nassau, and State of New York, have invented 5 an Improvement in Switch or Receptacle Boxes, of which the following is a specification.

My invention relates to the boxes of insulating material within which are contained 10 the mechanism of wall switches, the contacts of base receptacles or the like. Such boxes are contained in outlet boxes which are attached to, or embedded in the walls of a building, and which serve to support the switch box and provide a fireproof covering for the wiring.

It is desirable, particularly in the case of 15 flush switches and receptacles to so locate the switch box, that the face plate used for covering the switch and outlet boxes be finally located in a definite position. In the case of a flush switch or receptacle, the face plate should be so located as to make a good 20 contact with the plaster or other finished surface of the wall.

The general object of my invention is to 25 provide means for adjusting the position of the switch box with respect to the outlet box or other support upon which it is mounted.

In carrying out this object I provide a means 30 which is capable of rapid adjustment, by relatively inexperienced persons, thus saving a large part of the labor cost of installation, and a means which may be manipulated 35 to produce varying degrees of adjustment at the opposite ends of the switch or receptacle box.

I further aim to make such adjusting 40 means extremely simple and inexpensive to manufacture, and when installed of great strength and rigidity. A further object of my invention is to make the adjusting means semi-automatic in their operations, so that 45 when the position of the switch box is once arrived at, the switch box will be locked in position by the attaching of the box to the supporting means.

In the drawings I have shown in Figure 1 50 a switch box embodying my invention in an unadjusted position, that is, a position with respect to the plaster line that said box would not occupy. In Fig. 2 I have shown

the same box adjusted to the plaster line, and having the face plate attached, Figs. 1 and 55 2 being sectional side views. Fig. 3 is a front view of my improved switch box. Fig. 4 is a detailed view showing the channel which carries the adjusting lugs. Fig. 5 is a detailed perspective view of one of the adjusting lugs.

Referring to the drawings, 1 is an outlet 60 box or other supporting means which is embedded in or supported upon the wall of the building, as for instance, the plaster wall 2; 65 3 being the plaster line or line of the finished surface of the wall. The outlet box 1 carries lips 4 which are threaded to engage lug screw 5 by which the switch box 6 is attached to the outlet box 1.

At either end of the switch box 6 there is located a channel 7. Channel 7 may be conveniently formed of metal and attached to the switch box 6 in any suitable manner, as for instance by molding it in the switch box 75 when the switch box is made of molded insulation. Channel 7, however, may be formed in any suitable manner, and may be made if desired, of the material of the switch box 6 itself. In the drawings I have illustrated channel 7 as being made of some suitable metal as, for instance, brass.

Channels 7 may be of any suitable form, but I prefer to form them with a flat back 80 surface 8, which may be roughened or 85 ribbed, if desired, as shown in Fig. 4, and with a pair of lips 9 at their outer sides to engage the lugs, as will be described hereafter. It is entirely possible, of course, to otherwise arrange lips 9 and the channel 7 90 with respect to each other and to the switch box, for the purpose specified, and I therefore do not wish to limit myself to any particular construction of channel, but wish to be understood, when I refer to a channel, as 95 describing any suitable means for co-operating with the lugs, as will be described hereafter.

Mounted within channels 7 are lugs 10, which are preferably formed of one piece of 100 resilient material, such as brass. Lugs 10 are provided with holes 11, to engage attaching screws 5, at their outer ends, and are formed in a substantial U shape at their inner ends. The inner ends of lugs 10 may be 105 provided with shoulders 12, which engage

the inner surfaces of lips 9, upon channel 7, although said shoulders may be omitted if desired.

The material of lugs 10 is so proportioned 5 that when the bifurcated ends are brought together it will cause the U shaped inner ends of the lugs to bend. Thus in Fig. 1, the lugs are shown as having substantially, flat inner ends, the bifurcated outer ends being 10 separated. In Fig. 2 the bifurcated outer ends are brought together by screwing down the attaching screw 5, and this causes a deformation of the inner ends, springing said flat portions into curved portions and 15 bringing them into contact with the rear walls 8 of channels 7.

The operation of my improved device is as follows: Assuming parts to be in the position of Fig. 1, the switch box 6 is moved to its 20 proper position with respect to the plaster line, the lugs 10 sliding within the channel 7. When the switch box has been brought to the proper position, the attaching screws 5 are screwed home. This causes the bifurcated 25 ends of the lugs to be brought together thus causing the shoulders 12, on the upper and lower portions respectively of the lug 10, to slide toward each other along the inner surface of the lips 9 of channel 7, and causes 30 the flat inner portions of the lugs to be sprung into the shape shown in Fig. 2. The result is, that the lug 10 is securely clamped in place by bearing against the inner wall 8 of channel 7, and against the inner side of 35 lips 9 thereof. It will thus be seen that the switch box has been locked in place by the operation of the attaching screws 5, and that it is unnecessary to make use of any other lug locking or fixing means, than the movement of the attaching screws.

It will also be noted that when the parts are in the position shown in Fig. 2, the lug forms a very stiff braced structure, there being in effect, a double support between the 45 outlet box of the switch box.

The switch box 6 is provided with the usual cover or bridge plate 13 which is used to protect and support the switch mechanism. In order to make my improved apparatus simple to assemble, I provide the 50 channel 7 with a stop 14, to prevent the lug 10 from leaving the channel at its lower end, and I leave the upper end of the channel open. Lugs 10 may thus be slid into the 55 channels from the upper ends thereof. The cover or bridge plate 13 is provided with an extension 15 at each end thereof, which extends over the upper end of the channel, as shown in Fig. 3, thus preventing the lug 60 from leaving the channel at the upper end, when the switch is assembled.

The switch or receptacle box may be provided with the usual cover or face plate 16, such as illustrated in Fig. 2, but this forms 65 no part of my invention.

It will be understood that my invention is equally applicable to switch boxes, receptacle boxes and similar devices, and that when I have used the words "switch box" or a similar term in this specification and in my 70 claims, I intend to include all such similar analogous devices.

While I have only shown one form of my invention, I do not intend to confine myself thereto, since it is obvious that many modifications may be made without departing from its spirit, thus, for instance, the engagement between the lips 9 and shoulders 12 may be omitted and the stiffness of the lugs relied upon to produce the locking action, or the 75 action of the attaching screw 5 can be made to otherwise lock the switch box in place.

What I claim is:

1. In a device of the kind described, a switch box, a support therefor, a lug extending between the switch box and the support, and common means mounted independently of said switch box for attaching the lug to the support and locking the lug to the 80 switch box.

2. In a device of the character described, a switch box, a supporting member mounted thereon, a support, and means for attaching said supporting member to said support, the operation of said attaching means acting to 85 bring said supporting member into binding 90 relation to said switch box to position the latter.

3. In a device of the character described, a switch box, a supporting member mounted 100 thereon, a support, and means for attaching said supporting member to said support, the operation of said attaching means acting to deform said supporting member to bring 105 the same into binding relation to said switch box to position the latter.

4. In a device of the kind described, a switch box, a flexible lug mounted thereon and normally out of locking contact therewith, a support, and means for attaching 110 said lug to said support, the operation of said attaching means acting at the same time to bring said lug into locking contact with the switch box.

5. An adjustable switch, comprising a box 115 member, a lug slidably mounted thereon, and normally out of locking contact therewith, a support, and means for attaching said lug to said support, the operation of 120 said attaching means acting at the same time to bring said lug into locking engagement with the box member.

6. An adjustable switch, comprising a box member carrying a channel, a lug slidably mounted in said channel and normally out 125 of locking contact therewith, a support, and means for attaching said lug to said support, the operation of said attaching means acting at the same time to bring said lug into locking contact with the channel.

7. An adjustable switch, comprising a box member carrying a channel, a bifurcated lug slidably mounted in said channel and means for causing said lug to be deformed to bring it into locking engagement with the channel.
8. An adjustable switch, comprising a box member having a channel mounted thereon, a lug having a flat inner portion and attaching means for the lug, the operation of which will bend the flat portion of the lug to bring it into locking engagement with the channel.
9. An adjustable switch, comprising a box member, a channel having lips mounted thereon, a lug slidably mounted in said channel and having shoulders adapted to engage said lips and means for bringing said shoulders into contact with said lips.
10. An adjustable switch, comprising a box member, a channel having a back portion and lips, mounted thereon, a lug slidably mounted in said channel and means for bringing said lug into contact with both said back portion and lips.
11. An adjustable switch, comprising a box member, a channel mounted thereon and having a back portion and lips, a lug having a flat portion and shoulders, and means for deforming said lug, to bend the flat portion into contact with the back portion of the channel and bring the shoulders into contact with the lips.
12. An adjustable switch, comprising a box member having a channel, a flexible lug slidably mounted in said channel, and means mounted independently of said box for bringing the lug into contact with two sides of the channel.
13. An adjustable switch comprising a switch box having a channel, a flexible lug mounted thereon and attaching means for the lug adapted to deform the lug to bring it into contact with two sides of the channel.
14. An adjustable switch, comprising a switch box having a channel, a bifurcated lug slidably mounted thereon and means for bringing the separated portions of the lug together, to cause a locking engagement between it and the channel.
15. An adjustable switch, comprising a switch box, a bifurcated lug having a flat inner portion and means for bringing the separated portions of the lug together to cause the flat portion to bend.
16. An adjustable switch, comprising a switch box, a bifurcated lug slidably mounted thereon and having a flat inner portion and attaching means for the lug, adapted to bring the separated portions of the lug together, to cause the flat portion thereof to bend.
17. An adjustable switch, comprising a switch box, a lug mounted thereon and having a bifurcated outer end always out of contact with said box, lug supporting means, lug attaching means passing through the separated portions of the lug and adapted to bring them together.
18. An adjustable switch, comprising a switch box, a bifurcated lug having a flat inner portion, slidably mounted thereon, supporting means for the lug, and attaching means adapted to coöperate with the supporting means and to bring the separated portions of the lug together, to cause the flat portion to bend.
19. An adjustable switch, comprising a box member, carrying a channel having a flat side and lips, a bifurcated lug slidably mounted in said channel, supporting means upon which said lug is adapted to rest, and attaching means passing through the separating portions of said lug and adapted to bring them together, to bring the lug into locking engagement with the flat side and lips of the channel.
20. An adjustable switch, comprising a switch box, a channel having a flat back and lips, mounted thereon, a lug having a bifurcated outer end and an inner end provided with a flat portion and shoulders, supporting means for the lug, and an attaching screw passing through the separated outer ends of the lug into the supporting means and adapted to bring the separated ends together, to cause the inner end of the lug to bend, to engage the lips and flat back of the channel.
21. In a device of the kind described, a lug, a channel, within which said lug is adapted to slide, a fixed stop at the lower end of the channel and a removable cover projecting over the upper end of the channel.

In testimony whereof I have signed my name to this specification this 4th day of December, 1916.

WILLIAM J. NEWTON.
